BAKER'S REEL OVEN

Walter R. Reach, Audubon, N.J., assignor to Golden Glow Vending Company, Inc., Philadelphia, Pa., a corporation of Pennsylvania

Filed May 4, 1962, Ser. No. 69,971

Term of patent 14 years

(Cl. D81—10)

Fig. 1.

Fig. 2.

*Fig. 3.*FIGURE 1 is a front elevational view of a baker's reel oven embodying my new design, the rear being essentially plain;

The dominant features of my design reside in the portions shown in full lines.

I claim:

The ornamental design for a baker's reel oven, as shown and described.
